[57] CLAIM

The ornamental design for a lint brush or similar article, as shown.

DESCRIPTION

FIG. 1 is a left elevation view of a lint brush showing a first embodiment of my new design.

FIG. 2 is a top view of the first embodiment.

FIG. 3 is a front elevation of the first embodiment.

FIG. 4 is a rear elevation of the first embodiment.

FIG. 5 is a right elevation of the first embodiment.

FIG. 6 is a bottom view of the first embodiment.

FIG. 7 is a left elevation of a lint brush showing a second embodiment of my design.

FIG. 8 is a top view of the second embodiment.

FIG. 9 is a front elevation of the second embodiment.

FIG. 10 is a rear elevation of the second embodiment.

FIG. 11 is a right elevation of the second embodiment.

FIG. 12 is a bottom view of the second embodiment.

FIG. 13 is a left elevation of a lint brush showing a third embodiment of my design.

FIG. 14 is a top view of the third embodiment.

FIG. 15 is a front elevation of the third embodiment.

FIG. 16 is a rear elevation of the third embodiment.

FIG. 17 is a right elevation of the third embodiment.

FIG. 18 is a bottom view of the third embodiment.

FIG. 19 is a left elevation of a lint brush showing a fourth embodiment of my new design.

FIG. 20 is a top view of the fourth embodiment.

FIG. 21 is a front elevation of the fourth embodiment.

FIG. 22 is a rear elevation of the fourth embodiment.

FIG. 23 is a right elevation of the fourth embodiment.

FIG. 24 is a bottom view of the fourth embodiment.

FIG. 25 is a left elevation of a lint brush showing a fifth embodiment of my new design.

FIG. 26 is a top view of the fifth embodiment.

FIG. 27 is a front elevation of the fifth embodiment.

FIG. 28 is a rear elevation of the fifth embodiment.

FIG. 29 is a right elevation of the fifth embodiment.

FIG. 30 is a bottom view of the fifth embodiment.

FIG. 31 is a left elevation of a lint brush showing a sixth embodiment of my new design.

FIG. 32 is a top view of the sixth embodiment.

FIG. 33 is a front elevation of the sixth embodiment.

FIG. 34 is a rear elevation of the sixth embodiment.

FIG. 35 is a right elevation of the sixth embodiment.

FIG. 36 is a bottom view of the sixth embodiment.
